UNITED STATES PATENT OFFICE.

JOHN L. DAWES, OF PITTSBURG, PENNSYLVANIA.

DESIGN FOR A BOTTLE.

SPECIFICATION forming part of Design No. 21,412, dated March 22, 1892.

Application filed February 23, 1892. Serial No. 422,592. Term of patent 14 years.

To all whom it may concern:

Be it known that I, JOHN L. DAWES, of Pittsburgh, in the county of Allegheny and State of Pennsylvania, have invented a new and original Design for Bottles, of which the following is a full, clear, and exact description, reference being had to the accompanying drawings, forming part of this specification, in which—

10 Figure 1 is a front elevation of a bottle embodying the design. Fig. 2 is a horizontal section on the line II II of Fig. 1.

The design consists in a bottle having a body portion of substantially the outline shown in 15 the drawings, and hereinafter claimed.

As shown in the drawings, the bottle is quad-

rilateral in cross-section, having two opposite sides 2 3 substantially flat and having the other two sides 4 5 curved and outwardly convex. On one of the curved sides 4 is a recessed panel 6.

I claim—

The design for bottles, substantially as herein shown and described.

In testimony whereof I have hereunto set my hand this 15th day of February, A. D. 1892.

JOHN L. DAWES.
